UNITED STATES PATENT OFFICE.

JACOB FREISTADTER, OF WALTHAM, MASSACHUSETTS.

BALANCE-STAFF FOR WATCHES.

1,136,595.

Specification of Letters Patent. Patented Apr. 20, 1915.

Application filed October 7, 1914. Serial No. 865,473.

To all whom it may concern:

Be it known that I, JACOB FREISTADTER, a citizen of the United States, and resident of Waltham, in the county of Middlesex and State of Massachusetts, have invented certain new and useful Improvements in Balance-Staffs for Watches, of which the following is a specification.

This invention has for its object to provide a watch balance staff which is capable of being installed in a watch movement more conveniently and with greater facility than heretofore, and it is embodied in a reversible balance staff having the advantages which I will now proceed to describe and claim.

Of the accompanying drawings forming a part of this specification: Figure 1 represents a side view of a balance staff embodying my invention, shown on an enlarged scale, a portion of the balance, the hair spring collet, the roller table, the safety roller, and the jewels and endstones engaged with the staff being shown in section; Fig. 2 represents an end view of the staff.

The same reference characters indicate the same or similar parts in all the views.

My improved balance staff is composed of two duplicate end portions 12, each having a pivot 13, and each formed as an inverted facsimile of the other, and an intermediate collar 14 the ends of which form stop shoulders. The distance between the upper shoulder and the upper pivot 13 is the same as the distance between the lower shoulder and the lower pivot 13. The collar 14 enters a recess 16 in the hub 15 engaged with the arm 17 of the balance. The staff is adapted to be installed with either end up, that is, with either pivot 13 engaged with the upper jewel 18 in the balance cock or bridge 19, and the other pivot engaged with the lower jewel 20 in the lower watch plate 21. Either one of the duplicate end portions 12 is adapted to engage a hair spring collet 22 while the other engages a roller table 23 and a safety roller 24, said end portions being preferably slightly tapered, as shown, and adapted to have a close frictional engagement with the collet, safety roller, and roller table.

The chief advantage of the described reversible balance staff is convenience and facility in fitting the pivots 13 to the jewels

18 and 20. Said pivots and the bearings therefor in the jewels are liable to vary slightly in diameter, it being difficult if not impossible to make each pivot and bearing of exactly the same diameter as the other. I find that when the staff is of the described reversible construction, if the pivots and bearings do not fit each other satisfactorily when the staff is installed with one end up, the difficulty can be overcome by the simple expedient of reversing the staff. The duplicate form of the staff portions 12 enables the collet 22 to be engaged with the upper portion, and the safety roller 23 and the table roller 24 with the lower portion of the staff, it being immaterial which end of the staff is the upper end. The balance wheel is always located at the same relative height in the watch whether one end of the staff or the other is uppermost. By varying the depth of the recess 16 and the width of the collar 14, or both, the staff and collet can be properly installed in any watch. The reversibility of the staff practically doubles the opportunity of fitting the same to an already completed watch, and is therefore especially useful in American and foreign machine-made watches.

The fixed shoulders formed by the ends of the collar 14, and equidistant from the pivots 13, constitute duplicate oppositely facing stops, either of which is adapted to abut against the usual shoulder formed by the inner end of the recess 16 in the balance hub 15, so that the collar determines the height of the balance wheel on the staff whether one end of the staff or the other is uppermost. Said duplicate stops therefore do away with the necessity of experimental adjustment of the height of the balance on the staff, and insure the location of the balance at its proper height without trials and measuring, thus saving time and insuring accuracy in positioning the balance.

Having described my invention, I claim:

A reversible balance staff composed of duplicate end portions, each having a pivot and each formed to engage either a hair spring collet or a safety roller and a roller table, and an intermediate cylindrical balance hub-engaging collar the ends of which form duplicate oppositely facing stops, the distance between the upper stop and the upper pivot being the same as that between the

lower stop and the lower pivot, each end portion being practically an inverted facsimile of the other, whereby the staff may be installed with either end portion uppermost, and with either end portion engaged with a hair spring collet and the other end portion engaged with a safety roller and a table roller, the cylindrical form of said collar

permitting it to engage a balance hub with either end of the staff uppermost.

In testimony whereof I have affixed my signature, in presence of two witnesses.

JACOB FREISTADTER.
